ATTORNEYS.

UNITED STATES PATENT OFFICE.

WILLIAM C. EDGE, OF NEWARK, NEW JERSEY.

DESIGN FOR A CHAIN.

SPECIFICATION forming part of Design No. 27,087, dated May 25, 1897.

Application filed December 15, 1896. Serial No. 615,817. Term of patent 7 years.

To all whom it may concern:

Be it known that I, WILLIAM C. EDGE, a citizen of the United States, residing at Newark, in the county of Essex and State of New Jersey, have invented and produced a new and original Design for Chains; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The single figure of the drawing, showing the newly-designed chain in plan, is deemed sufficient to fully illustrate the invention.

The leading feature of my design consists in a chain which in configuration has a plurality of rope-like or twisted members disposed side by side, the twist of one member being a right-hand twist and the twist of the other being a left-hand twist, substantially as shown.

In said drawing, *a a'* represent a plurality

of rope-shaped twisted members of the chain, 25 one of which members *a* displays a right-hand twist, and the contiguous or adjacent member *a'* displays a left-hand twist. Each of the said members *a a'* is shaped and presents to view a collection of twisted cord-like 30 parts *a''*, which in turn are also of twist-shaped strands. The right-hand twist-shaped member is at one side of the left-hand member, the spirally-curved lines of one member diverging or converging from or toward those 35 of the other member, as indicated.

Having thus described the invention, I claim as new—

The design for a chain, substantially as herein shown and described. 40

In testimony that I claim the foregoing I have hereunto set my hand this 9th day of November, 1896.

WILLIAM C. EDGE.
